UNITED STATES PATENT OFFICE

AUGUST KIRILOW, OF PITTSBURGH, PENNSYLVANIA.

DESIGN FOR A PICTORIAL POST-CARD.

43,620.

Specification for Design.

Patented Feb. 25, 1913.

Application filed April 23, 1912. Serial No. 692,721. Term of patent 3½ years.

To all whom it may concern:

Be it known that I, AUGUST KIRILOW, a subject of the Czar of Russia, residing at Pittsburgh, county of Allegheny, and State of Pennsylvania, have invented a new, original, and ornamental Design for Pictorial Post-Cards, of which the following is a specification, reference being had to the accompanying drawing, forming part thereof.

The figure is a face view of a post card, showing my new design.

I claim:—

The ornamental design for a pictorial post card, as shown.

AUGUST KIRILOW.
